TYPEWRITING MACHINE

Henry Joseph Hart, West Hartford, Conn., assignor to Royal Typewriter Company, Inc., New York, N. Y., a corporation of New York

Application October 1, 1938, Serial No. 232,869

30 Claims. (Cl. 197—63)

This invention relates to typewriting machines and more particularly to stops for arresting or limiting movement of typewriter carriages in letter-spacing or return directions and to mechanism for adjustably positioning such stops.

It is usual to provide cooperating stop elements on typewriter main frames and carriages for arresting or limiting movement of the carriages either for fixing the writing margins or for positioning the carriage for tabulating operations. The illustrative embodiment of the invention to be described comprises a typewriter including carriage-mounted stops arranged to cooperate with a stop on the frame for fixing a margin of the typed sheet and mechanism for adjustably positioning the carriage-mounted stops. It will be understood, however, that the invention is adapted for more general application.

An object of the invention is to provide an improved form of adjustable stop for arresting or limiting letter-spacing or return movement of a typewriter carriage on the associated frame.

Another object is to provide mechanism co-operable with an adjustable stop for quickly and easily moving the stop along its support and automatically setting it in adjusted position.

A further object is to provide mechanism of the character referred to which is of simple construction, easy to operate, and certain in its action in correctly positioning the stop.

A further object is to provide a typewriter having a pair of adjustably mounted margin stops and mechanism for adjustably positioning the stops, the arrangement being such that the stops may be positioned by setting suitable control means, and moving the typewriter carriage to the desired margin positions.

Other objects will become apparent from a reading of the following description, the appended claims, and the accompanying drawings, in which:

Figure 1 is a fragmentary front elevational view of a typewriter carriage, showing parts of mechanism embodying the invention;

Figure 2 is a plan view of an assembly of some of the parts shown in Figure 1, some parts being shown partly in section;

Figure 3 is a front view of the parts shown in Figure 2;

Figure 4 is a perspective view of a margin stop assembly;

Figure 5 is a detail rear elevation of a center stop;

Figure 6 is a transverse vertical section, part-

ly in elevation, showing the carriage end plates and right hand margin stop control means;

Figure 7 is a fragmentary detail section taken on the line 7—7 of Figure 3, some parts being omitted for clarification.

Figure 8 is a fragmentary top plan view of parts as viewed when looking in the direction of the arrows 8—8 in Figure 3, and drawn on an enlarged scale;

Figure 9 is a fragmentary top view of parts as viewed when looking in the direction of the arrows 9—9 in Figure 3, and drawn on an enlarged scale;

Figure 10 is a perspective view of a portion of a margin stop releasing ball;

Figure 11 is a vertical section taken on the line 11—11 of Figure 8;

Figure 12 is a distorted diagrammatic plan view of a resilient stop-urging band and its mounting means;

Figure 13 is a fragmentary end elevation as viewed when looking in the direction of the arrows 13—13 in Figure 1, and showing an actuating lever in one position;

Figure 14 is a view similar to Figure 13 but showing the actuating lever in a different position; and

Figure 15 is a fragmentary view in end elevation showing a modification including a spring for holding a bail actuating lever against accidental displacement.

The drawings show only such of the usual parts of a typewriter as are necessary in order to make clear the manner of applying stops and stop-setting mechanisms embodying the invention to typewriters generally. The known or usual parts thus shown are of the form used in the Royal Standard typewriter and include a main-frame-mounted track A, a main frame rear wall part B, and a carriage C having a track I supported for letter-spacing and return movements on the track A by ball bearings 2. A platen or cylinder 3 is mounted in the usual manner between end plates 4 and 5 forming part of the carriage structure. A scale D is supported on the carriage as at 6—6 in the usual manner and is provided along its upper edge with a work sheet and typing aligning scale 7, and along its bottom edge with a carriage positioning scale 8. Central pointers 9 and 10 formed on a fixed type bar guide E cooperate with the scale 8 for assisting the operator to position the carriage. A center stop 11 of known kind is pivotally mounted at 12 on the frame wall B, and a line lock lever 13 is pivotally mounted as at 14 on the center stop 11 in a known manner. A

tabular stop mounting assembly F is supported on the carriage, being connected at its opposite ends to the end plates 4 and 5 as at 15 and 16 respectively.

5 In accordance with the disclosed embodiment of the invention, a stop is supported and normally locked in fixed position on the carriage for cooperation with the center stop 11 to arrest or limit movement of the carriage, the carriage-mounted stop being urged constantly toward the center stop. Means are provided for quickly and easily unlocking the carriage mounted stop so as to permit it to be moved by the constant urge until it contacts the center stop, after which 10 the carriage is moved to the desired margin position and the carriage-mounted stop then is locked to the carriage.

15 In the form shown, right and left hand margin stops, respectively designated G and G', are mounted on and for adjustment along a margin stop rod or bar H having transverse teeth 17 spaced along its upper face and being supported on and between the carriage end plates 4 and 5.

20 The left hand margin stop G includes a tubular body 18 formed with a lateral extension 19 which receives an adjustable abutment screw 20 adapted to cooperate with the center stop 11 in a manner to be described, a set screw 21 serving to hold the abutment screw 20 in adjusted position. A latch generally designated 22 is pivotally mounted as at 23 on the body 18, and is provided with a nose 24 adapted to fit between adjacent teeth 17 on the margin stop bar H for releasably locking or holding the stop G in 25 adjusted position on the bar H. The latch is formed with a horizontal arm 25 extending toward the center of the carriage, and a spring 26 held in place by a stud 27 is interposed between the body 18 and the horizontal arm 25 for yieldably urging the latch nose 24 toward the teeth 17 of the rod H. The free end of the horizontal arm 25 is provided with a roller 28 which functions for a purpose to be described later. Between the pivot 23 and the nose 24, the 30 latch is provided with an upstanding finger piece 29 which serves as a means for manually releasing the latch when desired. Preferably, a companion finger piece 30 extends upwardly from the body 18, so that, when it is desired to release the latch 22, the two finger pieces 29 and 35 30 may be grasped between the thumb and forefinger, and a squeezing action exerted.

40 The construction of the right hand margin stop G' is similar to that of the left hand stop G just described, the only difference being that it is reversed as to right and left hand. Accordingly, no detailed description of the right hand stop G' is necessary. The reversely similar parts of the two stops G and G' are designated by corresponding reference characters, the 45 characters applied to the stop G', however, being primed.

50 Means are provided for constantly urging both stops G and G' inwardly toward the center of the carriage and towards each other. It is one of the features of this invention that the means for providing this urge is extremely compact and is fitted in among adjacent typewriter parts neatly and without protruding, and it therefore 55 does not present the appearance of an additional appendage or attachment. The margin stop urging means is adapted to exert a light but sure and substantially uniform or constant pull on the margin stops irrespective of the relative positions of the stops. To this end the stop urging 60

means comprises a very long resilient band which is materially longer than the distance between the margin stops G and G' irrespective of the positions of the stops on the bar H. In the illustrative embodiment, the resilient band 55 comprises an elongated coil power spring I one end of which is connected to an ear 31' on the body 18' of the stop G'. From the ear 31' the spring I extends to the left as at 32, and around a sheave or roller 33 anti-frictionally journaled on a bracket 34 secured to the end plate 4 by a screw 35. The spring then extends to the right as at 36 and around a sheave or roller 33' anti-frictionally journaled on a bracket 34' secured to the end plate 5 by a screw 35' so as to rotate 10 about an axis inclined with respect to the axis of rotation of the roller 33. Thence the spring extends to the left as at 37, and is connected to an ear 31 on the body 18 of the stop G. The length of the spring I is such that, when 20 the stops G and G' are positioned near the center of the carriage, as indicated in dotted lines in Figure 1, in which position of the stops the spring will be in its most contracted position, the spring will be under substantial tension. 25

25 To assure a light and uniform tension or constant urge of the margin stops toward the center of the rod H, the coil spring band I is made extremely long. The length of the spring should be substantially greater than and preferably at 30 least twice as great as the distance between the stops G and G' in any adjusted position of the stops. In the form shown the spring is about three times as long as the length of either margin stop travel. The spring is made of such 35 length because it is important that substantially the same urging force be exerted on the margin stops G and G' irrespective of their positions on the bar H. In order that the spring function most efficiently in a construction embodying the 40 present invention, it should itself be of quite unusual formation. As applied to the Royal Standard eleven-inch typewriter, the contracted length of the preferred form of spring is about fifteen inches. When extended to its maximum length, 45 i. e., when the stops G and G' are in the full line position shown in Figure 1, the spring is about twenty-nine and one-eighth inches long, and, when the stops are in the position shown in dotted lines in Figure 1, the length of the 50 spring is about twenty-two and five-eighth inches. The differences between the length of the spring for different adjusted positions of the margin stops are small as compared to the total length of the spring, so that a substantially 55 uniform pull is exerted on the margin stops regardless of their positions.

55 The spring preferably is formed of music wire, and, in the Royal Standard eleven-inch typewriter, the wire used in forming the spring is 60 about three hundred and thirty inches long and about one hundredth of an inch in diameter. There are about ninety turns per inch, and thirteen hundred and fifty turns for the entire fifteen inches of spring. The generally accepted 65 practice in spring design is that a coiled spring can be extended with safety at least three times its unextended length. The wire spring band I, however, is extended only two thirds of its capacity, thus assuring great elasticity and durability, and entire lack of tendency to crystallize. 70

75 Because of its unusual construction, the spring band I is quite sensitive to extension or stretching, and it therefore is desirable that the sheaves or rollers 33 and 33' be mounted for very free rota- 75

tion. Otherwise binding or frictional drag resulting in non-rotation of the sheaves would localize the stretching action of the spring to a small portion of the spring rather than permit the entire length of the spring to stretch or expand simultaneously. In order that the urge exerted by the spring be substantially uniform, it should of course be tensioned or stretched uniformly throughout its entire length. For example, referring to Figure 12, suppose that the margin stop ear 31 is moved toward the left, and suppose that the roller 33' should fail to rotate, due to a frictional drag. The stretch 37 of the spring I would elongate to permit movement of the stop ear 31, and the stretches 32 and 36 of the spring would not elongate. Thus only a relatively small portion of the spring would be elongated, and consequently an unduly and undesired heavy pull would be imposed upon the stop ear 31. However, if the rollers 33 and 33' are so mounted as to roll very freely, then any movement of either one of the margin stops will stretch not only the immediately adjacent connected portion of the spring I, but will feed the spring around the rollers and stretch the spring uniformly throughout its entire length so as to provide a soft, easy, expanding and contracting action, making it possible to move the stops away from each other easily, and also providing a soft, easy action tending to draw the stops toward each other when they are released or unlatched from the margin stop bar H.

To provide the desired free journaling of the rollers, they are mounted by anti-friction ball bearings, the bearings for the right hand roller 33' being shown at 38' in Figure 7. Similar ball bearings, not shown, are provided for freely mounting the left hand roller 33.

In order to prevent accidental fouling or entanglement of the spring I with adjacent parts, a housing 39 substantially enclosing the entire spring and mounted under the margin stop bar H is secured to the brackets 34 and 34' as at 40 and 40'.

Control means conveniently located on the typewriter are provided for controlling the securing action of the latch 22 including releasing the latch so as to unlock the stop G from the bar H, permitting the spring I to draw the stop toward the right until arrested by the center stop 11. In the form shown, the control means includes a latch-releaser or bail J of generally inverted L shape having rearwardly extending arms 41 and 42 pivotally mounted as at 43-44 respectively on the tabular stop assembly F. The bail includes a horizontally extending ledge 45 which overlies the path of the roller 28 on the stop G. Normally, the bail is in elevated position, as shown in Figures 3 and 7, wherein the ledge 45 is above and out of contact with the roller 28. The pivotal mounting of the bail at 43 and 44 permits it to be moved downwardly to bring the ledge 45 into engagement with and to press on the roller 28 so as to raise the latch nose 24 to release or unlock the stop G from the stop bar H. When the latch is thus released, the spring I will pull the stop G to the right until the abutment screw 20 engages a buffer 46 which preferably is pivotally mounted on the center stop as at 14, a buffer spring 47 connected to the buffer element 46 and to the center stop serving to cushion the impact of the stop G.

The control means also includes releasable set-position-determining holding or locking means for maintaining the bail J set in its normal in-

active position out of contact with the roller 28, for moving the bail downwardly to its operative position to press the roller 28 down, and for releasably locking or maintaining the bail set in its lower latch-releasing or operative position to maintain the latch nose free of engagement with the stop bar H. In the illustrative embodiment shown, the releasable holding or locking means comprises a cam and follower device connected through the bail J to the latch roller 28. A ball-actuating lever 48 is pivotally mounted as at 148 on the carriage end plate 4, and is provided with a holding part formed with an eccentric cam slot 49 which receives a cooperating holding part comprising a cam follower stud 50 which has threaded connection on a projection 51 extending from the arm 41 of the bail J. A finger piece 52 integral with the bail-actuating lever 48 provides for easy manual operation of the lever. Forward movement of the lever 48 and 20 downward swinging movement of the bail are limited by engagement of the stud 50 with the inner or closed end of the slot 49. Rearward movement of the lever 48 is limited by engagement of the lever with a stop 53 eccentrically mounted 25 on a stud 54 connected to the carriage end plate 4.

The lever 48 is formed adjacent the open end of the cam slot 49 with a recess or seat 55 upon which the stud 50 is adapted to rest in definite 30 position to maintain the latch 45 of the bail above and out of contact with the latch roller 28. Proper seating of the stud 50 in the seat or recess 55 when the ball-actuating lever is in its rear position can be assured by adjusting the cam 35 stop 53 so that the lever 48 will engage the stop when the seat 55 has come directly under the stud 50. When the typewriter is in operation with the margin stop G in fixed position, the lever 48 will be in its retracted position in engagement 40 with the stop 53, and the stud 50 will rest in the seat 55 so as positively to prevent the bail J from being accidentally lowered into contact with the roller 28.

The shape of the cam slot 49 is such that, 45 when the lever 48 is moved forwardly, the stud 50 will be moved down by its engagement with the upper side of the cam slot, thereby swinging the bail J downwardly so as to bring the ledge 45 of the bail into contact with the roller 28, 50 pressing the roller downwardly and disengaging the latch from the toothed bar H. When the latch has thus been disengaged, the spring I will move the stop G to the right until arrested by the center stop in the manner already described. In order that the latch may be held or maintained in released position without its being necessary for the operator to hold the ball-actuating lever 48 in its forward position, the upper side of the cam slot 49 is formed with a 60 recess or seat 56 which receives the stud 50 when the lever 48 has been moved forwardly to the position shown in Figure 14. The depth of the recess 56 is such that, when the stud 50 is received in the recess, the bail J is locked down 65 in its latch-releasing position. Thus the bail actuating and holding lever 48 will remain in fixed position until manually released therefrom.

When it is desired to set the margin stop G in a position in which it will maintain a left 70 hand margin equivalent to twenty letter spaces on the typed sheet, the bail-actuating lever 48 will be pulled forwardly so as to move the bail J downwardly and to cause the bail ledge 45 to press upon the roller 28 and release the latch 75

22 in the manner already described. The spring I then will draw the margin stop G to the right until arrested by the center stop. If the carriage C is moved either to the right or to the left, the stop G will be held up against the center stop by the spring I. To "set" the stop G, the carriage is moved to the position in which the marking "20" on the scale 8 registers with the pointer 10 on the type bar guide E if the machine is set for lower case typing, or registers with the pointer 9 on the type bar guide E if the machine is set for upper case typing. The bail-actuating lever 48 will then be pushed rearwardly until it engages the stop 53, thus raising the bail to the position shown in Figure 13 and permitting the latch 22 to engage the stop bar H, thereby locking the stop G to the bar H while the stop is in operative engagement with the center stop. It is apparent that, if the carriage is moved to the left during the typing of a line and is then returned to the right, engagement of the stop G with the center stop will arrest return movement of the carriage when the pointer 9 or 10 registers with the scale marking "20", thus fixing the left hand margin as desired. The engagement of the stud 50 with the inner or closed end of the slot 49 of the lever 48 limits the movement of the bail J to a position in which the bail cooperates with or presses upon the roller 28 so as to hold the latch nose 24 disengaged from the bar teeth 17 without producing a frictional binding reaction between the bar H and the margin stop G or any part carried by the margin stop.

Similar control means is provided for releasing the latch 22' of the stop G' to permit setting of the stop G' for fixing the desired right hand margin. The control means associated with the stop G' includes a bail J' and a bail-actuating lever 48' similar to the bail J and actuating lever 48 already described, the only difference being that the bail J' and bail-actuating lever 48' are reversed as to right and left hand with respect to the bail J and actuating lever 48. Accordingly, no detailed description of the bail J' and actuating lever 48' is necessary. The reversely similar parts of the bail J' and actuating lever 48' are designated by reference characters corresponding to those designating similar or corresponding parts of the bail J and lever 48, the reference characters applied to the parts of the bail J' and lever 48', however, being primed. The operation of the lever 48' and bail J' for releasing the latch 22' is similar to the operation of the lever 48 and bail J for releasing the latch 22.

Assuming that it is desired to set the margin stop G so as to fix the left hand margin at twenty letter spaces, and that it is desired to set the stop G' so as to fix the right hand margin at seventy letter spaces, both levers 48 and 48' will be pulled forwardly, thereby releasing both latches 22 and 22' and permitting the spring I to pull the stops G and G' into engagement with the center stop. The carriage may then be moved until the pointer 9 or 10 registers with the marking "20" on the scale 8, and the lever 48 is then pushed rearwardly to the position shown in Figure 13, thus effecting locking of the margin stop G in adjusted position on the rod H. The carriage C may then be moved until the pointer 9 or 10 registers with the marking "70" on the scale 8 and the lever 48' pushed rearwardly to the position shown in Figure 6 so as to effect locking of the stop G' to the bar H.

The two stops G and G' will then be set so as to maintain the proper left hand and right hand margins on the typed sheet.

Alternately, the stops may be set in the following manner. First, the levers 48 and 48' are pulled forwardly to release both latches 22 and 22'. The carriage is then moved to its extreme right hand position, which will effect positioning of the stop G at its extreme outer or left hand position on the rod H. The lever 48 is then moved rearwardly to effect locking of the stop G to the rod H. The carriage is then moved to its extreme left hand position so as to locate the stop G' adjacent the right hand end of the rod H, after which the lever 48 is returned to its rear position to effect locking of the stop G' to the rod H. Then the carriage is moved until the pointer 9 or 10 registers with the scale mark "20," and the lever 48 is pulled forward to unlatch the stop G so as to permit the spring I to pull the stop G to the right until arrested by the center stop. The lever 48 will then be returned to its rearward position so as to effect locking of the stop G to the margin stop rod H. The carriage is then moved to the left until the pointer 9 or 10 registers with the scale mark "70." Then the lever 48' is pulled forward so as to unlatch the stop G' and permit the spring I to draw the stop G' to the left until it engages the center stop. Finally, the lever 48' is returned to its forward position, effecting locking of the stop G' to the bar H.

In both methods of setting the stops G and G' just described, the stop G is set first, and the stop G' afterward, but obviously either stop may be set first.

In the modification shown in Figure 15, the bail-actuating lever 48' is formed below the pivot 148' with a flat surface 58 adapted to cooperate with a spring 59 mounted on the carriage end plate 5 as at 60 and 61 for retaining the lever 48' in either its forward position or its rear position against accidental displacement.

It is apparent that new advantages and very desirable operating characteristics and results are obtained by using mechanism embodying the invention. In setting the adjustable stop or stops the operator need only manipulate conveniently located control means, and then shift the carriage to the desired location. It is not necessary for the operator to refer to special stop setting scales at the rear of the typewriter, reference to the usual carriage-locating scale or a previously typed or marked part of the work sheet being sufficient. Consequently it is possible for the operator to set the stop or stops quickly, easily, and surely without having to move from typing position or posture.

The mechanism disclosed herein embodies the invention in a practical and its at present preferred form, but it will be understood that various changes may be made without departing from the invention as defined in the claims.

I claim:

1. In a typewriter, a frame element; a carriage element mounted thereon for letter spacing and return movements; a first stop device mounted on one of said elements; a second stop device cooperable with said first stop device and being adjustably mounted on the other of said elements for movement to selected positions thereon in the direction of said movement of the carriage; means urging said adjustably mounted stop towards said other stop; means for releasably securing said adjustably mounted stop in selected position on its mounting element against the action of said

urging means; means for controlling the securing action of said securing means including a settable device adapted when moved to set position to maintain said securing means in released position; and set-position-determining means for releasably holding said device in said set position.

2. In a typewriter, a frame element; a carriage element mounted thereon for letter spacing and return movements; a first stop device mounted on one of said elements; a second stop device cooperable with said first stop device and being adjustably mounted on the other of said elements for movement to selected positions thereon in the direction of said movement of the carriage; means urging said adjustably mounted stop towards said other stop; means for releasably securing said adjustably mounted stop in selected position on its mounting element against the action of said urging means; and means including a cam and follower device operatively connected to said securing means for releasing the latter, said cam being formed with a depression adapted to receive said follower when the securing means is in released position.

25 3. In a typewriter, a frame element; a carriage element mounted thereon for letter spacing and return movements; a first stop device mounted on one of said elements; a second stop device cooperable with said first stop device and being adjustably mounted on the other of said elements for movement to selected positions thereon in the direction of said movement of the carriage; means urging said adjustably mounted stop towards said other stop; means for releasably securing said adjustably mounted stop in selected position on its mounting element against the action of said urging means; and means for controlling the securing action of said securing means including means for preventing accidental releasing of said securing means and for releasably maintaining the securing means in released position.

4. In a typewriter, a frame element; a carriage element mounted thereon for letter spacing and return movements; a first stop device mounted on one of said elements; a second stop device cooperable with said first stop device and being adjustably mounted on the other of said elements for movement to selected positions thereon in the direction of said movement of the carriage; means urging said adjustably mounted stop towards said other stop; means for releasably securing said adjustably mounted stop in selected position on its mounting element against the action of said urging means; operating means including a cam and follower device operatively connected to said securing means for releasing the latter, said cam being formed with a depression adapted to receive said follower when the securing means is in released position; and means for normally maintaining said operating means in inactive position to prevent accidental releasing of said securing means.

5. In a typewriter, a frame element; a carriage element mounted thereon for letter spacing and return movements; a first stop device mounted on one of said elements; a second stop device cooperable with said first stop device and being adjustably mounted on the other of said elements for movement to selected positions thereon in the direction of said movement of the carriage; means urging said adjustably mounted stop towards said other stop; a latch for releasably securing said adjustably mounted stop in selected position on its mounting element against the action of said urging means; a latch-releaser cooperable with

said latch at any position of said adjustably mounted stop on its mounting element; and holding means releasably settable in fixed position for maintaining said latch-releaser in latch-releasing position, said holding means being constructed and arranged to remain in said fixed position until manually released therefrom.

6. In a typewriter, a frame element; a carriage element mounted thereon for letter spacing and return movements; a first stop device mounted on one of said elements; a second stop device cooperable with said first stop device and being adjustably mounted on the other of said elements for movement to selected positions thereon in the direction of said movement of the carriage; means urging said adjustably mounted stop towards said other stop; a latch for releasably securing said adjustably mounted stop in selected position on its mounting element against the action of said urging means; a latch-releaser cooperable with said latch at any position of said adjustably mounted stop on its mounting element; and means for operating said latch-releaser and for releasably maintaining it in latch-releasing position, said means including a holding device releasably settable in fixed position for maintaining said latch-releaser in latch-releasing position, said holding device being constructed and arranged to remain in said fixed position until manually released therefrom.

7. In a typewriter, a frame element; a carriage element mounted thereon for letter spacing and return movements; a center stop mounted on said frame element; a margin stop cooperable with said center stop and being adjustably mounted on said carriage element for movement to selected positions thereon in the direction of said movement of the carriage; means urging said carriage-mounted stop towards said center stop; means for releasably securing said carriage-mounted stop in selected position on said carriage; means for controlling the securing action of said securing means including a settable device adapted when moved to set position to maintain said securing means in released position; and set-position-determining means for releasably holding said device in said set position.

8. In a typewriter, a frame element; a carriage element mounted thereon for letter spacing and return movement; a center stop mounted on one of said elements; a pair of spaced margin stops cooperable with said center stop and being adjustably mounted on the other of said elements for movement to selected positions thereon in the direction of said movement of the carriage; elongated resilient means under tension connected to said margin stops respectively and urging both margin stops toward said center stop; means mounting and so positioning said resilient means on the element which mounts the adjustable stop that the length of said resilient means between its points of connection to said margin stops is substantially greater than the distance between said margin stops in any adjusted positions thereof; and means for releasably securing said margin stops in selected positions on their mounting element.

9. In a typewriter, a frame element; a carriage element mounted thereon for letter spacing and return movement; a center stop mounted on one of said elements; a pair of spaced margin stops cooperable with said center stop and being adjustably mounted on the other of said elements for movement to selected positions thereon in the direction of said movement of the carriage; elong-

gated resilient means under tension connected to said margin stops respectively and urging both margin stops toward said center stop; means mounting and so positioning said resilient means on the element which mounts the adjustable stop that the length of said resilient means between its points of connection to said margin stops is at least twice as great as the distance between said margin stops in any adjusted positions thereof; and means for releasably securing said margin stops in selected positions on their mounting element.

10. In a typewriter, a frame element; a carriage element mounted thereon for letter spacing and return movement; a center stop on said frame element; a pair of spaced margin stops cooperable with said center stop and being adjustably mounted on said carriage element for movement to selected positions thereon in the direction of said movement of the carriage; elongated resilient means under tension connected to said margin stops respectively and urging both margin stops toward said center stop; means mounting and so positioning said resilient means on said carriage that the length of said resilient means between its points of connection to said margin stops is substantially greater than the distance between said margin stops in any adjusted positions thereof; and means for releasably securing said margin stops in selected positions on their mounting element.

11. In a typewriter, a frame element; a carriage element mounted thereon for letter spacing and return movement; a center stop on said frame element; a pair of spaced margin stops cooperable with said center stop and being adjustably mounted on said carriage element for movement to selected positions thereon in the direction of said movement of the carriage; elongated resilient means under tension connected to said margin stops respectively and urging both margin stops toward said center stop; means mounting and so positioning said resilient means on said carriage that the length of said resilient means between its points of connection to said margin stops is at least twice as great as the distance between said margin stops in any adjusted positions thereof; and means for releasably securing said margin stops in selected positions on their mounting element.

12. In a typewriter, a frame element; a carriage element mounted thereon for letter spacing and return movement; a center stop mounted on one of said elements; a pair of spaced margin stops cooperable with said center stop and being adjustably mounted on the other of said elements for movement to selected positions thereon in the direction of said movement of the carriage; a pair of spaced rollers journaled at opposite ends of the element on which said margin stops are mounted; an elastic band connected at its opposite ends to said margin stops respectively and passing around said rollers; and means for releasably securing said margin stops in selected positions on their mounting element.

13. In a typewriter, a frame element; a carriage element mounted thereon for letter spacing and return movement; a center stop on said frame element; a pair of spaced margin stops cooperable with said center stop and being adjustably mounted on said carriage element for movement to selected positions thereon in the direction of said movement of the carriage; a pair of spaced rollers journaled at opposite ends of the carriage element; an elastic band connected at its oppo-

site ends to said margin stops respectively and passing around said rollers; and means for releasably securing said margin stops in selected positions on the carriage element.

14. In a typewriter, a frame; a carriage mounted thereon for letter spacing and return movement; a center stop on said frame; a toothed bar on said carriage; a pair of margin stops mounted on and for adjustment along said bar and being cooperable with said center stop; releasable latches associated with the margin stops respectively and engageable with said bar for retaining the margin stops against movement on the bar; sheaves journaled on the carriage respectively adjacent opposite ends of said bar; and an elastic band connected to said margin stops and passing around said sheaves.

15. In a typewriter, a frame; a carriage mounted thereon for letter spacing and return movement; a center stop on said frame; a toothed bar on said carriage; a pair of margin stops mounted on and for adjustment along said bar and being cooperable with said center stop; releasable latches associated with the margin stops respectively and engageable with said bar for retaining the margin stops against movement on the bar; sheaves anti-frictionally journaled on the carriage respectively adjacent opposite ends of said bar; and a long coil spring connected at its opposite ends respectively to said margin stops and passing around said sheaves, said sheaves being so positioned on the carriage that the length of said spring between its points of connection to said margin stops is at least twice as great as the distance between said stops in any adjusted positions thereof.

16. In a typewriter, a frame; a carriage mounted thereon for letter spacing and return movement and having right and left hand ends; a center stop on said frame; a margin stop bar on said carriage; a right margin stop mounted on and for adjustment along said bar between the right hand end of the carriage and the center stop; a left margin stop mounted on and for adjustment along said bar between the left-hand end of the carriage and the center stop; releasable means associated with the margin stops for holding them in adjusted position on said bar; right and left hand rollers journaled on the carriage respectively adjacent the right and left hand ends thereof; and an elastic band connected at one end to said right margin stop, then extending to the left and around said left hand roller, then extending to the right and around said right hand roller, and then extending to the left and being connected to said left margin stop.

17. In a typewriter, a frame; a carriage mounted thereon for letter spacing and return movement and having right and left hand ends; a center stop on said frame; a margin stop bar on said carriage; a right margin stop mounted on and for adjustment along said bar between the right hand end of the carriage and the center stop; a left margin stop mounted on and for adjustment along said bar between the left hand end of the carriage and the center stop; releasable means associated with the margin stops for holding them in adjusted position on said bar; right and left hand rollers journaled on the carriage respectively adjacent the right and left hand ends thereof; and a coil spring band connected at one end to said right margin stop, then extending to the left and around said left hand roller, then extending to the right and around said right hand roller, and then extend-

ing to the left and being connected to said left margin stop, said spring band being formed of a length of wire about five times as long as the total length of the band when the right and left 5 margin stops are positioned respectively at the right and left hand limits of their travel on said rod.

18. In a typewriter, a frame; a carriage mounted thereon for letter spacing and return movement and having right and left hand ends; a center stop on said frame; a margin stop bar on said carriage; a right margin stop mounted on and for adjustment along said bar between the right hand end of the carriage and the center stop; a left margin stop mounted on and for adjustment along said bar between the left hand end of the carriage and the center stop; releasable means associated with the margin stops for holding them in adjusted position on said bar; right and left hand rollers journaled on the carriage respectively adjacent the right and left hand ends thereof; and an elastic band connected at one end to said right margin stop, then extending to the left and around said left hand roller, then extending to the right and around said right hand roller, and then extending to the left and being connected to said left margin stop, said rollers being mounted to rotate about axes mutually inclined with respect to each other 25 whereby adjacent passing stretches of said band 30 will be free from contact with each other.

19. In a typewriter, a frame element; a carriage element mounted thereon for letter spacing and return movement; a center stop mounted on one of said elements; a pair of spaced margin stops cooperable with said center stop and being adjustably mounted on the other of said elements for movement to selected positions thereon in the direction of said movement of the carriage; 40 a pair of spaced rollers journaled at opposite ends of the element on which said margin stops are mounted; an elastic band connected at its opposite ends to said margin stops respectively and passing around said rollers; a housing for 45 said band mounted on said margin-stop-mounting element and extending between said rollers; and means for releasably securing said margin stops in selected positions on their mounting element.

50 20. In a typewriter, a frame element; a carriage element mounted thereon for letter spacing and return movement; a center stop mounted on one of said elements; a pair of spaced margin stops cooperable with said center stop and being adjustably mounted on the other of said elements for movement to selected positions thereon in the direction of said movement of the carriage; an elastic band connected at its opposite ends to said margin stops respectively; spaced band- 55 supporting devices mounted respectively adjacent opposite ends of the margin-stop-supporting element and around which said band is passed and adapted to move freely; and means for releasably securing said margin stops in selected positions on their mounting element.

55 21. In a typewriter, a frame element; a carriage element mounted thereon for letter spacing and return movement; a center stop on said frame element; a pair of spaced margin stops cooperable with said center stop and being adjustably mounted on said carriage element for movement to selected positions thereon in the direction of said movement of the carriage; an elastic band connected at its opposite ends to said margin 70 stops respectively; spaced band-supporting de-

vices mounted respectively adjacent opposite ends of the carriage element and around which said band is passed and adapted to move freely; and means for releasably securing said margin stops in selected positions on the carriage element. 75

22. In a typewriter, a frame; a carriage mounted thereon for letter spacing and return movement and having right and left hand ends; a center stop on said frame; a margin stop bar on said carriage; a right margin stop mounted 10 on and for adjustment along said bar between the right hand end of the carriage and the center stop; a left margin stop mounted on and for adjustment along said bar between the left-hand end of the carriage and the center stop; 15 releasable means associated with the margin stops for holding them in adjusted position on said bar; right and left hand band-supporting devices mounted on the carriage respectively adjacent the right and left hand ends thereof; and an elastic band connected at one end to said right margin stop, then extending to the left and passing around said left hand band-supporting device for free movement relative thereto, then extending to the right and passing around said 20 right hand band-supporting device for free movement relative thereto, and then extending to the left and being connected to said left margin stop.

23. In a typewriter, a frame element; a carriage element mounted thereon for letter-spacing and return movements; a center stop mounted on one of said elements; a margin stop cooperable with said center stop and being adjustably mounted on the other of said elements for movement to selected positions thereon in the direction of said movement of the carriage; resilient means urging said margin stop towards said center stop; means for releasably securing said margin stop in adjusted position on its mounting element against the action of said urging means; an operating member for releasing said securing means; and releasable holding means associated with said operating member for releasably fixing the position of said member to maintain said securing means released. 45

24. In a typewriter, a frame; a carriage mounted thereon for letter-spacing and return movements, a center stop on said frame; a toothed margin stop bar on said carriage; a margin stop cooperable with said center stop and being mounted 50 for adjusting movement longitudinally on said bar; a spring-pressed latch on said margin stop engageable with selected teeth on said bar for normally and releasably holding said margin stop in adjusted position on said bar; a spring-powered device connected to said margin stop and urging it toward said center stop; an operating member pivoted on said carriage and extending longitudinally of and adjacent said bar and being movable to inactive position in which it has no 55 effective operative connection with said latch and to operative position in which it operatively connects with the latch and holds the latch out of operative engagement with the toothed bar; and means for releasably maintaining the operating 60 member in operative position, said means including two parts movable relatively one to the other and comprising a first part fixed to the operating member and a coacting part mounted on the carriage and contacting said first part. 65

25. In a typewriter, a frame; a carriage mounted thereon for letter-spacing and return movements; a center stop on said frame; a toothed margin stop bar on said carriage; a margin stop cooperable with said center stop and being mount- 70 75

- ed for adjusting movement longitudinally on said bar; a spring-pressed latch on said margin stop engageable with selected teeth on said bar for normally and releasably holding said margin stop 5 in adjusted position on said bar; a spring-powered device connected to said margin stop and urging it toward said center stop; an operating member pivoted on said carriage and extending longitudinally of and adjacent said bar and being movable to inactive position in which it has no effective operative connection with said latch and to operative position in which it operatively connects with the latch and holds the latch out of operative engagement with the toothed bar; 10 and means for releasably maintaining said operating member in inactive position including a part connected to the operating member and being movable therewith and a coacting part mounted on the carriage, one of said parts being formed with a seat and the other of said parts having a projecting portion adapted to be received by said seat when the operating member 15 is in inactive position.
26. In a typewriter, a frame; a carriage mounted thereon for letter-spacing and return movements; a center stop on said frame; a toothed margin stop bar on said carriage; a margin stop cooperable with said center stop and being mounted for adjusting movement longitudinally 20 on said bar; a spring-pressed latch on said margin stop engageable with selected teeth on said bar for normally and releasably holding said margin stop in adjusted position on said bar; a spring-powered device connected to said margin stop and urging it toward said center stop; an operating member pivoted on said carriage and extending longitudinally of and adjacent said bar and being movable to inactive position in which it has no effective operative connection with said latch and to operative position in which it operatively connects with the latch and holds the latch out of operative engagement with the toothed bar; and means including a part connected to said operating member and a coacting part mounted on said carriage for releasably holding said operating member selectively in said inactive and operative positions depending on which position it has been moved to.
27. In a typewriter, a frame; a carriage mounted thereon for letter-spacing and return movements; a center stop on said frame; a toothed margin stop bar on said carriage; a margin stop cooperable with said center stop and being mounted for adjusting movement longitudinally 30 on said bar; a spring-pressed latch on said margin stop engageable with selected teeth on said bar for normally and releasably holding said margin stop in adjusted position on said bar; a spring-powered device connected to said margin stop and urging it toward said center stop; an operating member pivoted on said carriage and extending longitudinally of and adjacent said bar and being movable to inactive position in which it has no effective operative connection with said latch and to operative position in which it operatively connects with the latch and holds the latch out of operative engagement with the toothed bar; and means including a holding part 35 operatively connected to said operating member and a spring part adapted to press against different portions of said holding part selectively for yieldably holding said operating member selectively in said inactive and said operative positions depending on which position it has been moved to.
28. In a typewriter, a frame; a carriage mounted thereon for letter-spacing and return movements; a center stop on said frame; a toothed margin stop bar on said carriage; a margin stop cooperable with said center stop and being mounted for adjusting movement longitudinally 40 on said bar; a spring-pressed latch on said margin stop engageable with selected teeth on said bar for normally and releasably holding said margin stop in adjusted position on said bar; a spring-powered device connected to said margin stop and urging it toward said center stop; an operating member pivoted on said carriage and extending longitudinally of and adjacent said bar and being movable to inactive position in which it has no effective operative connection with said latch and to operative position in which it operatively connects with the latch and holds the latch out of operative engagement with the toothed bar; and means including a holding part 45 operatively connected to the operating member and yieldably resisting movement thereof from its operative position and from its inactive position, depending upon which position it has last been moved to.
30. In a typewriter, a frame; a carriage mounted thereon for letter-spacing and return movements; a center stop on said frame; a toothed margin stop bar on said carriage; a margin stop cooperable with said center stop and being mounted for adjusting movement longitudinally 50 on said bar; a spring-pressed latch on said margin stop engageable with selected teeth on said bar for normally and releasably holding said margin stop in adjusted position on said bar; an actuating part on said latch adapted to be pressed for releasing the latch from tooth-engaging position; a power spring connected to said margin stop and urging it toward said center stop; an operating member mounted on said carriage and extending longitudinally of and adjacent said bar and being movable to inactive position in which it has no effective operative connection with said actuating part, and to operative position in which it operatively connects with and presses said actuating part to move and hold the latch out of operative engagement with the toothed bar, whereby said power spring is enabled to move said margin stop toward said center stop while said latch-actuating part maintains operative contact with said operating member; and limit- 55
- 75 75

ing means independent of said actuating part for fixing the limit of operating movement of the operating member to a position in which said member cooperates with said actuating part to hold said latch disengaged from said bar teeth without producing a frictional binding reaction between said bar and said margin stop or any part carried thereby, whereby, when said operat-

ing member is moved to the fixed position determined by said limiting means, said power spring will move said margin stop along the bar and against said center stop with the latch-actuating part moving along and in contact with but unrestrained by said operating member. 5

HENRY JOSEPH HART.
